UNITED STATES PATENT OFFICE.

THOMAS J. PARK, OF RENSSELAER, MISSOURI.

DESIGN FOR A WASHER.

SPECIFICATION forming part of Design No. 23,551, dated August 7, 1894.

Application filed July 11, 1894. Serial No. 517,255. Term of patent 14 years.

To all whom it may concern:

Be it known that I, THOMAS J. PARK, of Rensselaer, in the county of Ralls and State of Missouri, have invented and produced a new and original Design for a Washer, of which the following is a full, clear, and exact description.

Reference is to be had to the accompanying drawings, forming a part of this specification, in which similar letters of reference indicate corresponding parts in both the figures.

Figure 1 represents a perspective view of a washer embodying my new design; and Fig. 2 an edge view thereof.

The leading feature of my design consists in the novel configuration of the washer, which presents a circular opening and a mar-

ginal edge circular for the major portion and concentric to the central opening, the marginal edge at one side being of greater radius 20 than the remaining portion and presenting a concavo-convex extension as seen in side view. A minor feature is the surface formation, consisting of a beveled rectangular figure forming a border for the central opening 25 as shown.

I claim—

The design for a washer herein shown and described.

THOMAS J. PARK.
